AMIDOALKYLAMINE GLYCERIDE WAX
 Harland H. Young, Western Springs, and Kurt H. Spitzmueller, Clarendon Hills, Ill., assignors to Swift & Company, Chicago, Ill., a corporation of Illinois
 No Drawing. Filed Jan. 8, 1962, Ser. No. 164,972
 2 Claims. (Cl. 260—404.5)

This invention relates to fatty compositions and, more particularly, to fatty materials substituted with amino fatty amido radicals and to the manufacture of such compositions.

Condensation products of amines and fatty acids and derivatives thereof have been prepared heretofore and have been found useful for a variety of applications such as surface-active agents, corrosion inhibitors and in the production of resins.

It has now been found that a particular type of new condensation product derived from amines and fatty compositions having properties simulating natural waxes and synthetic waxes can be prepared from fatty amido amines and fatty acids and derivatives thereof.

It is accordingly an object of this invention to provide new fatty acids, fatty acid esters, fatty acid amides and fatty alcohols substituted along the fatty chain with fatty amido amino radicals.

Another object of the invention is the provision of a method for producing new fatty compositions having fatty amido amino radicals substituted along a fatty chain.

Additional objects of the invention if not specifically set forth herein will be readily apparent to those skilled in the art from the detailed description of the invention which follows.

Generally the compositions of this invention comprise chain substituted higher fatty acids, esters of such higher fatty acids, fatty amides and fatty alcohols having substituted on adjacent carbons in an aliphatic chain a hydroxyl group and a fatty amido amino group. This alpha amido amino-hydroxy substitution may occur one or more times in a given fatty chain, generally one to five times, and the fatty acid portion of the fatty amido amino radical, as well as the amido portion of the fatty amido amino radical, can be varied widely. The compositions are waxlike materials exhibiting strong adherence to surfaces on which they are deposited such as glass, metal, etc. The tackiness of many of the compositions renders them very satisfactory for use as ingredients in waxes, adhesives and in the lamination of porous and nonporous materials such as sheets of metal foil, insulation paper, etc.

More particularly, the compositions of the invention can be characterized as higher fatty acids, esters of such higher fatty acids, higher fatty alcohols and, higher fatty amides having chain substituted hydroxyl and amido amino groups characterized by the structure:

where Y is selected from the group consisting of aliphatic hydrocarbon chains containing 1-6 carbons either unsubstituted or having aliphatic hydrocarbon side chains, and amino alkylene radicals of 1-18 carbon atoms and 1-8 nitrogen atoms and R is an aliphatic hydrocarbon radical of 9-27 carbons.

The composition prepared by condensing the monoamido of 1,3 diamino propane and stearic acid with

2

epoxidized butyl oleate, for example, can be represented by the structure

10

Amino amides contemplated as the amine supplying reactants in the formation of the waxy condensation products are generally fatty acid monoamides of aliphatic polyamines. Suitable fatty acids include those of the type 10-28 carbon saturated and unsaturated monocarboxylic aliphatic hydrocarbon acids such as lauric, myristic, palmitic, margaric, stearic, arachidic, undecylenic, oleic, lauroleic, palmitoleic, ricinoleic, myristoleic, linolenic, linoleic, gadoleic and erucic acid. The saturated, monoethenoic, diethenoic and triethenoic acids all can be employed. The fatty acids and mixtures of fatty acids derived from naturally occurring animal, vegetable and marine triglycerides such as coconut oil, palm oil, castor oil, cotton seed oil, soybean oil, linseed oil, safflower oil, tall oil, tallow, herring oil, sardine oil and whale oil represent a convenient source of the higher fatty acids. The partially and completely hydrogenated derivatives of these triglycerides are also contemplated.

30 Polyamines useful in forming the amido amines include those straight chain aliphatic polyamines having more than one amino nitrogen and having from 2-10 carbon atoms. Typical non-hydroxylated aliphatic polyamines which can be employed in the formation of the amine 35 substituted amides include ethylene diamine, propylene diamine, butylene diamine, 1,3 diamino propane, 1,3 diamino hexane, tetramethylene diamine, ditheylene triamine, dipropylene triamine, triethylene tetramine, penta-methylene diamine, tetraethylene tetramine, tetraethylene 40 pentamine pentaethylene hexamine, nonaethylene decamine, and other primary and secondary aliphatic diamines, triamines, tetraamines, pentamines and hexamines. Also suitable are the N-alkyl amino alkylamines. There is no particular limit on the number of carbons and 45 amino groups in the polyalkylene polyamines which can be used but because of the lack of availability compositions having about 2-18 carbons and 2-10 nitrogens are recommended.

The amine reactive fatty derivatives employed in formation of the waxlike compositions comprise higher fatty acid derivatives having amine reactive substituents such as oxirane groups or halo-hydroxy groups on the fatty chain. Oxirane substituted higher fatty acids and higher fatty acid derivatives include those compositions such as 50 partially and completely epoxidized higher fatty acids, esters, alcohols, etc., which contain one or several epoxy groups at those places in the molecule which before epoxidation existed as ethylenic unsaturation.

Esters of higher epoxy fatty acids such as those produced by the epoxidation of animal, vegetable and marine 55 glycerides comprise a typical group of derivatives capable of reacting with the amino alkyl acid amides. The lower aliphatic alcohol esters of such acids can also be employed as the amine reactive composition. Lower monohydric alcohol esters having 1-8 carbons in the alcohol, as well as dihydric alcohol esters having 1-8 carbons, can also be employed. The trihydric, tetrahydric, pentahydric and hexahydric alcohol esters are also satisfactory materials for reactions with the amine substituted 60 monoamido.

70 The epoxidized naturally occurring glyceride esters of higher fatty acids represent a very satisfactory source for

this component of the compositions because of their ready availability.

The halo hydroxy fatty acids and derivatives thereof are less preferred amine reactive materials but again represent a large group from which selection can be made. Included within this group are the higher fatty acids and derivatives of such higher fatty acids having hydroxy and halo groups substituted on at least one fatty chain. The chlorine substituents are preferred over the bromine and iodine substituents insofar as the halo group is concerned. The materials are prepared by adding a hypohalous acid across the double bonds of an unsaturated fatty acid or derivative thereof such as undecylenic acid, palmitoleic acid, ricinoleic acid, oleic acid, petroselinic acid, linoleic acid, linolenic acid and arachidonic acid. The fatty acid components for both the halo hydroxy and the epoxy fatty acid derivatives are substantially the same. Both the epoxidized fatty acid and halo hydroxylated fatty acid are prepared by known reactions. Very desirable epoxidized or halo hydroxylated derivatives are obtained by epoxidizing or halo hydroxylating naturally occurring glycerides having ethylenic unsaturation. Suitable animal, vegetable and marine triglycerides which, when treated with epoxidizing reagents or halo hydroxylating reagents to produce the corresponding epoxides or halo hydroxylated compounds are soybean oil, cotton seed oil, tallow, linseed oil, safflower oil, herring oil, sardine oil, tung oil, and tall oil among others.

The compositions of the invention can be prepared by reacting the monoamide of an aliphatic polyamine and a long chain fatty acid or fatty acid ester with a fatty composition having amine reactive substituents on a fatty chain. The amino amides are prepared by heating and reacting a polyamine with a higher fatty acid or higher fatty acid ester until the carboxyl group is amidated and a fatty acid amide having an available amine substituent is formed. The reaction is promoted by heating approximately molar equivalents of the fatty acid and amine or by heating about molar equivalents of the amine with an ester of such higher fatty acids. Stoichiometric amounts are generally preferred although a slight excess of the polyamine supplying material is preferred to depress the amount of diamide formed as an undesired by product. In some cases $\frac{1}{3}$ -1 mole of the acid will be reacted with $\frac{1}{2}$ -3 moles of the polyamine. Heating of the reactants either in the presence of a solvent or in the absence of a solvent to a temperature sufficient to initiate reaction is sufficient to produce the amino amides. Ordinarily a temperature above about 100° C. will be employed and the reaction mixture will be agitated. Completion of the reaction is more rapidly attained at higher temperatures while lower reaction temperatures require longer reaction times. Any amine volatilized during the course of the reaction should in the interest of economy be returned to the reaction zone. It has been found that the reaction can be carried out very easily and the reaction time shortened by the use of superatmospheric pressures. Under such conditions of about 20-300 pounds per square inch pressure and temperatures in the range of 150 - 215° C., a smooth reaction with good yields and without loss of the more volatile amine is realized.

The amino monoamide and epoxidized fatty material are reacted by heating the monoamide having amino groups and about a stoichiometric amount of the epoxide at a temperature above about 100° C. for 1-5 hours or until the epoxy content of the oxirane containing material reaches a minimum. By stoichiometric amount of the epoxide, it is intended that enough of the epoxy derivative be employed to insure that one epoxy group be present for each available amino group in the amino amide. The condensation reaction proceeds much more slowly at 100° C. than at higher temperatures and is usually completed in about one hour at 200° C. Superatmospheric conditions (20-200 pounds per square inch) are preferred

inasmuch as undesirable side reactions can be minimized if the reaction is conducted under positive pressure. The reaction between the oxirane containing material and the monoamide is particularly useful in the treatment of hard waxes such as those characterized as fatty acid diamides of 1,3 diamino propane. These hard waxes are disclosed and claimed in a copending application. In the preparation of the hard waxes a small amount of residual monoamide is present in the wax and the epoxy material when reacted with the monoamide enhances the adhesion of the hard wax to smooth surfaces.

The following examples which are included herein for purposes of illustrating the invention show the production of some of the waxy products of the invention.

Example I

One mole (284 grams) of stearic acid are mixed with one mole (74 grams) of 1,3 diamino propane and heated with stirring in a pressure vessel. The reaction is run for 2 hours at 200° C. The pressure does not exceed 170 p.s.i. which represents the steam pressure from the water of reaction. At the conclusion of the reaction period, the product is cooled to about 150° C. and transferred to a steam deodorizer. The deodorization is carried out at 2-5 mm. mercury pressure using steam as the stripping agent. The temperature is gradually raised to 200° C. to yield essentially N-stearoyl-1,3 diamino propane. This product is transferred to a pressure vessel and reacted with 176 grams of epoxidized linseed oil having an oxirane content of 9.1%. After heating at 200° C. for 5 hours with stirring the product is cooled to 150° C. before being exposed to the air. The final product is a firm but tacky wax like material.

Example II

One third of a mole (313 grams) of hydrogenated fish oil are reacted in a pressure vessel at 215° C. with one mole (74 grams) of 1,3 diamino propane. The contents of the vessel is heated and stirred for 3 hours during which time the maximum pressure does not exceed 30 p.s.i. At the conclusion of the reaction period, the product is cooled to below 150° C. and transferred to a deodorizer where the librated glycerol is removed by the use of steam and vacuum. When the temperature reaches 200° C. and the pressure drops to 1-2 mm. Hg, the stripping can be considered essentially complete. The product is cooled under vacuum to 130 - 150° C. and poured into pans to yield substantially pure hydrogenated fish oil fatty acid monoamide of 1,3 diamino propane. The product is assayed by titrating a sample in boiling neutral isopropyl alcohol and titrating with N/2 hydrochloric acid using bromo cresol green as an indicator. To a quantity of this monoamide containing one mole equivalent of amino-groups are added 229 grams of epoxidized soya bean oil having an oxirane content of 7%. This supplies an equivalent amount of oxirane content to react with each amino group. The mixture is then heated in a sealed vessel with stirring at 150° C. for 5 hours. At the conclusion of the reaction period, the product is cooled in trays to yield an adhering wax which will fracture when subjected to a sharp blow.

Example III

One mole of 58° titre hydrogenated tallow (876 grams) is placed in a pressure vessel with one and one-half moles of 1,3 diamino propane (114 grams). The reaction is run with agitation for 2 hours at 200° C. The pressure does not exceed 20 p.s.i. since water is not a by-product. At the end of the reaction time, the product is blown into the deodorizer where free glycerine settles out. The product is then deodorized with steam at a pressure of 5 mm. Hg and a temperature of 155 - 200° C. The vapors of the deodorization are conducted through an air condenser and finally through freezing trays to a vacuum source. Viscous glycerine distills and condenses in the air condenser starting at about 150° C. This removal of

glycerine accelerates with rising temperature, reaching a maximum at 175-180° C. in about 1 hour. The temperature is slowly increased to 200° C. by which time no further glycerine comes over. The heat source is removed and the contents of the deodorizer are cooled under vacuum in a continuing atmosphere of water vapor. At 140° C. the product is removed and chilled in a cold metal tray.

Glycerine recovered from the air condenser is 87% of the theoretical quantity and titration of the total condensate indicates the loss of amine as being less than 2%. A product made in this manner assays about 10% as monoamide. Such a wax separates from any hard smooth surface but can be given adhering properties by reacting the mono amide amine portion with epoxidized fats. Thus, the above product, about 900 grams, contained 90 grams of the amino-amide (0.28 mole) which in turn will require 4.47 grams of oxirane oxygen or 64 grams of epoxidized soya bean oil. The reactants in this ratio were heated in a pressure vessel at 150° C. for 3 hours. After cooling to 140° C., the product is cast onto trays for cooling. The product has adhering properties but can be removed by vigorous scraping. Analysis for oxirane content shows that practically all of the oxirane oxygen groups have reacted.

Example IV

One mole of coconut oil (654 grams) and three moles of 1,3 diamino propane (222 grams) are placed in a pressure vessel and heated for 5 hours with stirring at 150° C. The product is then stripped of glycerine under vacuum using steam and the product used directly for reacting with 600 grams butyl epoxystearate (8% oxirane). The mixture is heated in a pressure vessel for 3 hours at 150° C. The final product is a highly plasticized, adhering waxlike composition.

Example V

One mole of castor oil fatty acids (296 grams) are reacted with 1 mole of 1,3 diamino propane (74 grams) at 215° C. for 3 hours with agitation under pressure. Upon completion of the reaction, the pressure which has built up to 190 p.s.i., is released and the product cooled to 150° C. in the absence of air. The cooling creates a slight vacuum which is utilized to draw 178 grams of epoxidized linseed oil (16 g. oxirane oxygen) into the pressure vessel. The reactants are reheated to 210° C. for 2 hours with agitation. At the completion of the reaction, the product is deodorized with steam at 200° C. and 5 mm. Hg pressure to remove impurities. Upon cooling, wax-like product is cast into slabs.

Example VI

One mole of castor oil (934 grams) and three moles of ethylenediamine (180 grams) are reacted at 180° C. under pressure. The reaction product is used directly for reaction with epoxidized linseed oil. Thus 533 grams of epoxidized linseed oil are added and heated with stirring until the epoxide content reaches a minimum, usually 2 hours at 200° C. The final product is steam deodorized at 150-200° C. and 2-5 mm. Hg pressure to remove odors and volatile by-products.

Example VII

One mole (280 grams) of linoleic acid are reacted with one mole (114 grams) of 1,3 diaminopropane at 200° C. for 3 hours. The reaction is carried out in a pressure vessel with agitation. The pressure of the water vapor produced does not exceed 200 p.s.i. At the end of the three hour reaction period, the water vapor is vented until the internal pressure is equalized. 297 grams of epoxidized oleyl alcohol (containing 5.4% oxirane oxygen) are pumped into the reactor and reacted with the amino amide by heating to 100° C. for five hours with agitation. At the completion of the reaction, the product is run into suitable molds to yield a tough, tacky somewhat pliable wax.

Example VIII

One mole of erucic acid (332 grams) and one mole of butylene diamine (90 grams) are heated at 150° C. for 5 hours. The pressure is vented periodically to allow most of the water to escape. A small amount of amine is lost simultaneously but this is of no practical significance. At the end of the reaction period the pressures are equalized and one mole of methylchlorohydroxy-stearate (348 grams) is introduced. The reaction is completed by heating for 3 hours at 150° C. followed by 2 hours at 200° C. After venting, the product is deodorized at 150-200° C. and 2-5 mm. Hg pressure. After cooling to 160° C., the product is cast into slabs to yield a high melting but tacky wax.

Example IX

One mole of palmitic acid (256 grams) and one half mole (37 grams) 1,3 diamino propane are heated in a pressure vessel with agitation at 215° C. for 4 hours. The product is cooled to 150° C. and deodorized at 2-5 mm. Hg pressure at 150-200° C. The final product has about 3% monoamide amino compound as determined by titration. The reaction product is returned to the pressure vessel and reacted with 5.4 grams of epoxidized linseed oil (0.03 moles oxirane oxygen) at 200° C. for 2 hours. The final product after cooling to 150° C. is drawn off yielding an essentially natural high melting wax with enhanced adhesive properties.

Example X

One mole (938 grams) of castor oil and 3 moles (507 grams) of tetra ethylenepentamine are heated under pressure with agitation at 160° C. for 5 hours. The reaction product is stripped of its free glycerol by a steam deodorization under vacuum. To the waxy product are added 3 moles (685 grams) of epoxidized soya bean oil (oxirane oxygen=7%) and the mixture heated at 180° C. for 3 hours to react with all primary amino functions. The wax made by such a process has excellent tack but lends itself to easy removal by solutions having a low pH.

Example XI

One mole of undecylenic acid (184 grams) and one mole of 1,5 diamino pentane (82 grams) are heated in a pressure vessel with stirring to 175° C. for 4 hours. The volatile by-products are steam stripped in a deodorizer under vacuum at 200° C. for 15 minutes. The final product is condensed with one mole of 9,10 (10,9) chlorohydroxy stearyl alcohol (321.5 grams) by heating 150° C. for 5 hours. The reaction product is a medium melting point wax having good adhering properties with a certain amount of fungicidal properties.

As has been mentioned previously, the compositions of the invention possess a high degree of polarity and therefore adhere well to smooth surfaces such as glass and metal. The wax-like materials which are similar in many respects to beeswax are mildly basic in reaction and afford good protection against corrosion to surfaces on which they are coated.

Obviously many modifications and variations of the invention as hereinbefore set forth may be made without departing from the spirit and scope thereof and therefore only those limitations should be imposed as are indicated in the appended claims.

We claim:

1. A waxlike glyceride prepared by the process of reacting a monoamide of a $C_{10}-C_{28}$ fatty acid and an alkylene polyamine consisting of carbon, hydrogen and nitrogen and having 2-28 carbons and 2-10 nitrogens with a fatty composition selected from the groups consisting of epoxidized glycerides and haloxyhydroxylated glycerides, said reaction being conducted at a temperature of between about 100° C. and 200° C. for about 1-5 hours whereby to produce said waxlike glyceride.
2. Waxlike glycerides having 9-27 carbon atoms in each alkyl chain and having a hydroxyl group and amido

amino group attached to adjacent carbons in said chain, said chain having about 1-5 of said groups, said amido amino groups having the structure

wherein Y is selected from the groups consisting of alkylene radicals of 1-6 carbons and amino alkylene radicals of 1-8 carbons and 1-8 nitrogen atoms and R is an aliphatic radical of 9-27 carbons, said glycerides being prepared by reacting a monoamide of a C₁₀-C₂₈ fatty acid and an alkylene polyamine consisting of carbon, hydrogen and nitrogen and having 2-18 carbons and 2-10 nitrogens with a fatty composition selected from the group consisting of epoxidized triglycerides having 9-27 carbon atoms in each alkyl chain and halohydroxylated triglycerides having 9-27 carbon atoms in each alkyl chain, said

reaction being conducted at a temperature of between about 100° C. and 200° C. for about 1-5 hours whereby to produce said waxlike glycerides.
